UNITED STATES PATENT OFFICE.

WILLIAM J. JOHNSON, OF BOSTON, MASSACHUSETTS.

DRYING APPARATUS.

SPECIFICATION forming part of Letters Patent No. 228,259, dated June 1, 1880.

Application filed April 8, 1880. (No model.)

To all whom it may concern:

Be it known that I, WILLIAM J. JOHNSON, of Boston, in the county of Suffolk and State of Massachusetts, have invented certain Im-
5 provements in Drying Apparatus, of which the following is a specification.

My invention relates more especially to that class of drying apparatus used in printing es-
tablishments for drying the matrices from
10 which stereotype-plates are cast; and it con-
sists in an improved method whereby the work is more perfectly performed than by the
ordinary method, and with great economy of
time, and also in the apparatus for carrying
15 said method into effect, all of which is herein-
after more fully set forth and explained, ref-
erence being had to the drawings accompa-
nying and forming part of this specification, in
which—

20 Figure 1 shows an elevation, and Fig. 2 a transverse section, of the apparatus embody-
ing my invention.

In most daily-newspaper establishments where the paper has a very large circulation
25 it is usual to stereotype or reproduce the forms in order to delay going to press as long as pos-
sible, and then work off the edition with suffi-
cient rapidity. The matrices used in casting
such stereotype-plates are produced by tak-
30 ing an impression of the forms by means of a
pulpy composition applied to the face of the
type under pressure, the matrix so produced
being afterward carefully dried and removed.

It is obvious that the whole operation of pro-
35 ducing and drying the matrix in this manner
and in a limited time must necessarily be a
very rapid one in order to make it available.
By the method of drying ordinarily pursued
the matrices are placed upon a heated bed be-
40 fore being removed from the forms, and are
covered with blankets for the absorption of
the moisture, and are then subjected to pres-
sure from an ordinary flat press-platen. By
this method evaporation is retarded by the
45 use of the blankets, and vexatious and expen-
sive delays frequently occur on account of the
difficulty experienced in drying the matrices
properly and in season.

My invention is designed to obviate these
50 difficulties; and to that end I subject the ma-
trix to the pressure of a cushion of dry com-

pressed air in such a manner as to secure a uniform pressure upon all parts of its outer surface, whereby the matrix is kept perfectly flat upon the drying-bed, and thus prevented 55 from warping.

To secure the removal of the moisture evapo-
rated from the matrix, I permit a limited es-
cape of the compressed air composing the
cushion at points outside of the margin of the 60 matrix, the escape being sufficient to remove
the moisture as fast as it leaves the matrix
without materially reducing the pressure of
the cushion thereon.

In the application of this improved process 65
I make use of an improved apparatus, which
I will now specifically describe.

In the drawings, P represents the drying-
bed usually employed in drying the matrices.

A represents a hollow metallic air-chamber, 70
of sufficient size to cover the matrix when
placed upon the bed. This chamber may be
raised or lowered for the introduction or re-
moval of the matrix by means of the screw S,
75 attached to the wheel W.

D represents an induction-pipe for the in-
troduction of dry compressed air from proper
compressing apparatus into the chamber A to
form a cushion of air pressing equally upon
all parts of the outer surface of the matrix. 80

c c e are eduction-orifices in the sides of the
chamber to allow a limited escape of the air
outside of the margin of the matrix. These
orifices, while sufficiently large for the pur-
pose intended, are not large enough to dimin-
ish materially the pressure of the compressed
air upon the matrix. 85

It is obvious that these orifices may be of
the form shown, or may be simple notches cut
in the lower edge of the sides of the chamber; 90
or slight elevations might be made on the sur-
face of the bed, so as to prevent the chamber
from fitting closely in every part, and thus
leave a small vent for the escape of the com-
pressed air, without departing from the spirit 95
of my invention.

To prevent undue pressure in any event
upon the sides of the chamber or upon its top,
the safety-valve S' is attached.

In operation the drying-bed P is heated by 100
the introduction of steam into its interior, or
by any other suitable means. The chamber

A is raised and the matrix placed upon the surface of the bed. The chamber is then lowered and dry compressed air forced into it through the induction-pipe D. The compressed air forms a cushion, pressing evenly upon the matrix in every part and maintaining it firmly upon the drying-bed and preventing it from warping in the process of drying. The heat of the bed causes the rapid evaporation of the moisture in the matrix, which moisture is removed by the limited escape of the air, as above described. In this manner the matrix may be dried in a very short time and more perfectly than by the ordinary method, while the entire operation is much simpler and more convenient than that usually employed.

In the method heretofore employed it is necessary to place the matrices upon the heated bed before removing them from the forms. The heat is found to be injurious to the types, causing them to adhere and requiring them to be knocked apart before they can be distributed, and so rendering them liable to become misshapen. The alternate heating and cooling to which the type is subjected in repetitions of the drying process also seriously impairs its durability.

By my improved process above described, and by the use of my improved apparatus, it is possible to dry the matrices after they have been removed from the forms as well as before removal, thus preventing the injury to the type ordinarily incurred.

The compressed air introduced into the chamber may be either hot or cold; but as hot air will materially facilitate the drying process, I prefer its use.

Though primarily intended for drying the matrices used in casting stereotype-plates, my invention is equally applicable for drying any article formed of plastic material molded while wet, and which is required to be confined upon a rigid bed, either flat or of other form, while being dried.

I am aware that in drying the gummed backs of postage-stamps a current of warm air has been forced by a rotating fan upon the gummed surface; but I am not aware that in any apparatus of this nature a cushion of compressed air has ever been confined over the sheet to be dried so as to press uniformly

on all parts of its outer surface and prevent it from warping during the drying operation. Such a pressure is of the first importance in drying matrices.

Having thus described my invention, what I claim is—

1. The method of holding a matrix while it is being dried, consisting in supporting the matrix upon a rigid bed and applying to its outer surface a cushion composed of compressed air, which is supplied by a suitable compressing apparatus, and is confined over the matrix to exert a uniform pressure on the entire outer surface of the latter and prevent it from warping, as set forth.

2. The method of holding a matrix and conducting moisture therefrom, consisting in supporting the matrix upon a rigid bed and applying to its outer surface a cushion composed of compressed air, which is supplied by a suitable compressing apparatus, and is confined over the matrix to exert a uniform pressure on the entire outer surface of the latter, and is allowed to escape at points outside of the margin of the matrix sufficiently to carry off the moisture from the matrix without materially reducing the pressure of the cushion thereon, as set forth.

3. As a means for applying a cushion of compressed air to a matrix, the combination of the matrix-supporting bed and the movable chamber open on the side adjacent to the bed, and provided with an induction-pipe communicating with a suitable air-compressing apparatus.

4. The hollow metallic air-chamber A, provided with an induction-pipe, D, and an eduction orifice or orifices of smaller capacity than the induction-pipe, in combination with a heated bed, P, for subjecting the matrices used in casting stereotype-plates to a continuous current of compressed air, substantially in the manner and for the purpose set forth.

In testimony whereof I have signed my name to this specification, in the presence of two subscribing witnesses, this 27th day of March, A. D. 1880.

WILLIAM J. JOHNSON.
